UNITED STATES PATENT OFFICE.

BARTHOLOMEW JULIEN, OF OMAHA, NEBRASKA, ASSIGNOR TO CAMEL COMPANY, OF CHICAGO, ILLINOIS, A CORPORATION OF ILLINOIS.

DOOR-OPERATING MECHANISM.

Application filed August 2, 1923. Serial No. 655,207.

This invention relates to improvements in door operating mechanisms.

Heretofore great difficulty has been experienced in opening and closing the sliding side doors of box or other house type of cars on account of the tendency of the doors to become jammed or stuck. This is especially the case where doors of heavy construction and supported by either overhead or bottom tracks are used, the tracks and co-acting bearings becoming corroded due to exposure to the weather during continued service, thereby offering undue resistance to the movement of the doors, making the opening and closing thereof extremely difficult. In practice, it often happens, therefore, that the men in charge of opening and closing the doors are compelled to use crowbars or other tools to start the opening thereof and to force the same to closed position, consequently, seriously damaging the doors and requiring frequent and expensive repairs.

One object of the invention is to provide a simple and relatively inexpensive device which can be applied to doors of the type above indicated and which will have effective and easily-operated means for starting the opening of the doors and which will also draw the doors to tightly closed position.

Another object of the invention is to provide a door operating mechanism for opening and closing doors, which will readily accommodate itself to such variations as may occur in the manufacture and assembling of the parts, and to such distortion as may occur in service.

In the drawings forming a part of this specification, Figure 1 is a side elevational view of a portion of a car showing one embodiment of the invention in connection therewith, the same illustrating a double side door construction, parts being broken away to better accommodate the view to the sheet. Figure 2 is a horizontal longitudinal sectional view corresponding substantially to the line 2-2 of Figure 1. Figure 3 is a vertical transverse sectional view corresponding substantially to the line 3-3 of Figure 1. Figure 4 is a vertical sectional view corresponding substantially to the line 4-4 of Figure 3. Figures 5 and 6 are enlarged detailed side and edge elevational views, respectively, of a modified form of latch member adapted for use in connection with the embodiment of the invention shown

in Figures 1 to 4, inclusive. Figure 7 is a side elevational view of a portion of a car illustrating a different embodiment of the invention in connection with a single door construction, parts being broken away to better accommodate the view to the sheet. Figure 8 is a horizontal longitudinal sectional view corresponding substantially to the line 8-8 of Figure 7. Figure 9 is a vertical sectional view corresponding substantially to the line 9-9 of Figure 7. Figure 10 is a vertical sectional view corresponding substantially to the line 10-10 of Figure 9. And Figures 11 and 12 are detailed side and edge elevational views, respectively, of a modified form of latch member adapted to be used in connection with the embodiment of the invention illustrated in Figures 7 to 10, inclusive.

In said drawings, referring first to the embodiment of the invention illustrated in Figures 1 to 4, inclusive, in which the invention is shown in connection with a double sliding side door construction, 20 indicates the main door and 21 the auxiliary or smaller door of the usual double sliding door arrangement of a box or house car. In the form shown, the doors are of top-hung type provided with the usual roller brackets having rollers riding upon a track supported at the top of the door opening. The auxiliary door is provided at the front end thereof with the usual sliding door post 22 having means at the upper and lower ends thereof for preventing the front edge of the door from being sprung outwardly, comprising castings 23 secured respectively to the upper and lower end portions of the post 22 and co-operating with brackets 24 secured respectively to the door lintel and the floor boards of the car, the casting 23 and the bracket 24 at the lower end of the door only being shown in the drawing. The casting and bracket herein illustrated are of usual and well-known construction, the casting 23 being bolted to the lower end of the post and provided with a T slot co-operating with the T head on the bracket 24, the latter being suitably secured to a floor board. The inter-engaging T slots and heads prevent lateral movement of the front edge of the door when in closed position. The casting is also provided with a stop lug 26 adapted to coact with the T head of the bracket to limit the closing movement of the

door 21. Means is also provided on the auxiliary door 21 for latching the same in closed position—in this instance being shown as a vertically slidable bolt 26'. The front or adjacent edges of the doors 20 and 21 are protected by the usual metal covering, the door 20 being provided with an angle section 27 and the door 21 being provided with an angle section 28.

16. The improved door operating mechanism, as illustrated in Figures 1 to 4, inclusive, comprises, broadly, a housing A; a slidable bar B; an operating handle C; a sector gear D; and a latch member E.

17. The housing is preferably in the form of a box-like casting having spaced outer and inner side walls 29 and 30, relatively narrow front, rear and top walls 31, 32 and 33, and a short bottom wall 34 extending rearwardly from the front wall 31. The housing A is provided with suitable perforated ears 35, 36 and 37 by which it is secured to the door 21. The ear 35 is in the form of a central projection extending rearwardly from the wall 30 and the ears 36 and 37 are each in the form of spaced parallel members extending from the outer and inner side walls 29 and 30, respectively, united at their front edges by a strengthening web. As is clearly shown in Figures 1 and 2, the door 21 is suitably recessed, as indicated at 38, to receive the housing A, the recess 38 being of such a depth that the outer face of the outer side wall of the housing lies flush with the outer surface of the door, with the front end of the housing extending beneath the outer member of the angle section 28 and the front end engaging the inner face of the member of the angle section extending along the front edge of the door. The housing A is rigidly secured to the door 21 by a bolt 39 passing through the door and the lug 35 and a pair of bolts 40 extending through the post 22, angle plate 28 and the respective lugs 36 and 37.

18. The bar B is slidably mounted within the housing A bearing on the outer and inner side walls 29 and 30 and is guided on its upper edge by the top wall 33. The front and rear walls of the housing are provided with aligned openings 41 and 42 adapted to accommodate the opposite ends of the bar for sliding movement, the lower horizontal edge walls of the openings acting as guides for the lower edge of the bar. Additional guiding means for the lower edge of the bar is provided by an inwardly projecting short flange 43 extending from the front wall 31 of the housing adjacent the opening 41. The bar B is provided with a T head 42 at the front end thereof, the angle section 28 and the door being suitably recessed, as indicated at 44, to accommodate the same, so that when the bar is in its extreme retracted position, the front end face of the T head will

lie flush with the front face of the angle section 28 and the angle sections 27 and 28 may be brought into flat abutting relation and the T head will abut the section 27 when the doors are closed. One of the arms 70 of the T head 42 is extended outwardly beyond the face of the door, providing a pin-like member 44' integral therewith and adapted to be engaged by the latch E. The lower edge of the bar B is provided with a ratchet 45 with which co-operates the sector gear D.

19. The sector gear D is fixed to the operating handle C and is adapted to be rotated by the latter to reciprocate the bar B, the upper end of the handle C being provided with a lateral pivot extension 46 having a relatively large cylindrical bearing portion 47 adjacent the handle journaled in the boss 48 on the side wall 29, a relatively smaller cylindrical bearing portion 49 near the opposite end journaled in the boss 50 of the side wall 30 and an intermediate portion 51 of square cross section adapted to fit within a square opening 52 of the gear 90 D. The intermediate square portion of the lateral extension 46 is of such size in cross section as to freely pass through the bearing opening in the boss 48 and bear on the inner side of the wall 30 immediately adjacent the opening in the boss 48, the diagonals of the square cross section thereof being preferably equal in length or shorter than the diameter of the cylindrical portion 47, and the sides of the square cross sectional portion being preferably each of a diameter equal to, or greater than, the diameter of the cylindrical portion 49. It will be evident that with the parts thus constructed, the handle C and the gear D may be readily assembled within the housing by placing the gear between the side walls of the housing with the opening 52 thereof aligned with the openings in the bosses, and inserting the square portion of the pivotal extension of the handle into the opening of the gear by passing the same through the opening in the wall 29 and seating the cylindrical bearing portions 47 and 49 in the openings of the lugs 48 and 50, respectively.

20. As clearly shown in Figures 1 and 2, the operating handle C is enlarged adjacent the pivotal extension, thereby providing a bearing shoulder 53 adapted to abut the outer face of the lug 47. The free end of the pivotal extension is provided with a reduced threaded portion adapted to receive a nut 53'. The operating handle lever C extends through the open bottom of the housing A and has its swinging movement in a clockwise direction limited by engagement of the front edge of the gear sector D with the beveled upper edge 68 of an upstanding flange 69 on the short lower wall 34 of the housing. The operating handle lever C is

preferably offset to space the hand-grip portion thereof the proper distance from the outer side of the door to give sufficient clearance for the operator's hand. Where the operating handle cannot be given the proper amount of offset due to restrictions as to the overall width of the car, I preferably hinge the hand-grip to the handle proper, and, as clearly shown in Figures 3 and 4, the lower end of the handle proper is provided with a tongue 55 on which the hand-grip 56 is pivotally mounted, the latter having its upper end slotted to receive the tongue 55, thereby providing a pair of lugs 57 receiving the pivot pin 58 passing through the tongue 55 at right angles to the axis of rotation of the operating handle. To limit the outward swinging movement of the hand-grip, the handle and hand-grip are provided adjacent the pivotal connection thereof with co-acting stop lugs 59 and 60, as most clearly shown in Figure 3.

The latch member E is pivotally mounted on the door 20 by a bolt 61 passing through the door and one end of the plate 62 mounted on the outer side of the door, the other end of the plate being secured to the door by a second bolt, or any other suitable means. The portion of the bolt which extends through the plate and the door is reduced in diameter thereby providing a bearing portion 63 of relatively larger diameter on which the latch E swings and a shoulder 64 adapted to abut the outer face of the plate 62. It will be evident that by providing the shoulder 64 the head of the bolt will be spaced a predetermined distance from the plate to permit the free swinging movement of the latch. To properly space the latch from the door, a boss 65 through which the bolt 61 extends is provided on the inner side of the latch at the pivoted end thereof. At the free end the latch E is provided with a hook portion 66 adapted to co-act with the pin 44 of the T head 42, the latter being provided with a head 67 to prevent accidental disengagement of the hook therefrom.

Assuming the parts in the position shown in Figures 1 and 2, when it is desired to open the doors the operating handle lever C is swung to the left, as viewed in Figure 1, moving the bar B to the right, the latter positively forcing the door 20 away from the door 21, since the bar B has the T head thereof in abutment with the front edge of the door 20. The swinging movement of the lever may be continued until limited by engagement of the gear sector D with the flange 69, as shown in dotted lines in Figure 4. When the door has been thus partly opened, the latch E may be disengaged from the pin and the doors 20 and 21 fully opened by merely pushing the same in the usual manner. When it is desired to close

the doors, the door 21 is first moved to closed position, then the door 20 is moved to a position as near the front edge of the door 21 as can be conveniently done by the operator without the use of tools. The bar B is then moved outwardly as far as necessary and the hook end of the latch engaged with the pin thereof, after which the operator swings the handle C downwardly in a contra-clockwise direction, thus positively pulling the door 20 to fully closed position.

Referring next to the construction of the latch shown in Figures 5 and 6. The latch F shown in these figures is provided with a series of teeth 70 and a hook 71 at the front end thereof. As clearly shown in these figures, the teeth 70 have their front edges 73 inclined upwardly and forwardly. In all other respects the latch F is similar to the latch E and may be used in place of the latter in the construction illustrated in Figures 1 to 4 inclusive. The use of the latch F gives a greater working range of the device than the latch E during the door closing operation. When it is desired to close the main door, the latter may be moved to a position with reference to the auxiliary door so that the hook 71 or any one of the teeth 70 engage with the pin of the sliding bar. Assuming that the door has been moved to a position where the hook 71 engages the pin of the bar, it will be evident that an oscillating movement of the operating handle will intermittently pull the latch toward the auxiliary door, due to the ratcheting of the teeth 70 over the pin, thus pulling the main door to closed position. It will also be evident that the operation will be the same if the main door is so positioned with reference to the auxiliary door that any one of the teeth 70 engages the pin. In opening the door, the T head on the sliding bar, which is in abutment with the edge of the door 20, will effect movement of the door in a manner similar to that described in connection with Figures 1 to 4, inclusive.

Referring next to the embodiment of the invention illustrated in Figures 7 to 10, inclusive, in which the same is shown in connection with a single door construction, 116 indicates the side wall of a box car, 117 a section of the door stop, 118 one of the door posts or jams—the one near the front edge of the door, 119 the inner sheathing of the car and 120 the sliding door. The door 120 is of a top-hung type provided with the usual roller brackets having rollers riding on tracks supported at the top of the door opening. The door 120, as shown, is also provided with the usual protecting angle section 121 at its front edge.

The improved door operating mechanism, as illustrated in Figures 7 to 10, inclusive,

comprises, broadly, a housing A'; a slideable bar B'; an operating handle C'; and a latch member E'.

The housing A' is generally the same as the housing A, with the exception that the former is provided with only one securing lug 135 and the stop flange upstanding from the bottom wall of the housing is omitted, the operating handle C' being limited in its movement in a clockwise direction by engagement with the lower edge 132' of the rear wall 132 of the housing, movement of the lever in the opposite direction being limited by engagement with the door stop 117. The lug 135 extends rearwardly from the inner side wall 130 of the housing and is offset laterally toward the car wall, as clearly shown in Figure 8. The housing A' is secured in fixed position on the car by a bolt 139 passing through the lug 135 and the wall 116, and a pair of short bolts 140 extending through the front end portion of the housing and the door stop 117, the door stop being cut away at the rear side to accommodate the housing, the door stop being, in turn, bolted to the door jam 118.

The reciprocating bar B' is provided with a laterally outwardly projecting arm 142 at the front end thereof, having a portion thereof reduced and extended outwardly beyond the outer face of the door stop providing a pin 144 having an enlarged rounded head 167. The door stop is suitably recessed, as indicated at 143, to accommodate the arm 142, so that when the bar is in its extreme retracted position the front end face of the arm will lie flush with the front edge of the door stop and the angle section 121 may be brought into abutment therewith. The bar B' is slidably mounted within the housing A' similarly to the bar B, being guided between the side walls 129 and 130, having its upper edge guided by the top wall 133, its front and rear end portions working in the openings 141 and 142, respectively, and its lower edge guided by the flange 143.

The lower edge of the pull bar B' is also provided with a rack 145 with which co-operates a sector gear member D' formed integral with the operating handle C'. The operating handle C' is pivotally mounted between the walls 129 and 130 upon a pivot pin 146 passing through the walls and having a rivet head at one end and having the opposite end riveted over to retain it in position. The operating handle C' extends through the open bottom of the housing A' and the lower end portion thereof is offset, as shown, to space the hand-grip portion thereof the proper distance from the outer side of the door to give sufficient clearance for the operator's hand.

The latch E' and the mounting thereof is in all respects similar to the latch E previously described, with the exception that

the spacing boss adjacent the pivot bolt is omitted. The latch E' is provided with a hook portion 166 adapted to engage the pin on the reciprocating bar B' and is pivotally mounted on the door 120 by the shouldered bolt 161 passing through one end portion of the plate 162 and the door 120, the opposite end of the plate being bolted or otherwise secured to the door. The operation of the device shown in Figures 7 to 10, inclusive, is in all respects similar to that previously described.

Referring next to the construction shown in Figures 11 and 12, the latch F' shown is in all respects similar to the latch F shown in Figures 5 and 6, with the exception that the boss at the pivoted end is omitted. The rack F' is provided with teeth 170 and a hook 171, the operation thereof being identical with the latch F previously described.

Although the mechanism shown in Figures 1 to 9, inclusive, has been illustrated in connection with a double door construction, and the mechanism shown in Figures 10 to 12, inclusive, has been illustrated in connection with a single door construction, it will be evident that the former construction is adapted equally well for use with single doors and the latter construction is adapted equally well for use with a double-door construction.

It will be evident, upon reference to the preceding description taken in connection with the drawings that an exceedingly effective and simple door opening and closing mechanism is provided, in which all the parts are at all times clear of the door opening when the door is in open position, the latch, which is the only part that swings beyond the door opening, being swung downwardly clear of the door by the action of gravity when disengaged from the bar B. There will be no parts projecting into the door opening to hinder the loading or unloading of the car, thus eliminating the danger of breaking the parts, as will be understood.

With the arrangement which I have provided, a strong pushing force can easily be obtained to force the door open and an equally effective pulling force to close the same, even when the door may be badly sagged or distorted, and in this way I am enabled to eliminate the undesirable use of crowbars or other tools which have hitherto been found necessary in many instances.

I claim:

1. In a car, the combination with a main door and an auxiliary oppositely sliding door, said doors having their adjacent edges protected by angle sections; a housing fixed to the auxiliary door; a reciprocable rack bar mounted within said housing and extending through the angle section of the door, said bar being provided with a T head

- having a laterally extending portion projecting beyond the outer side of the door, said T head being adapted to abut the front edge of the angle section of the main door; 5 a lever operatively connected to said bar for reciprocating the same; and a latch pivotally mounted on the main door adapted to co-operate with said extension of the T head.
2. In an operating mechanism for relatively 10 slidable door members, slidable relatively to each other in a common plane; an actuating element slidably associated with one of said door members, said element being operable within the plane of said doors and 15 adapted to bear against the edge of one of said door members, said actuating element being provided with projecting means extending outside of the plane of movement of said doors; and means secured to said other 20 door member outside of the plane of movement thereof, said means being adapted to be detachably engaged with said projecting means.
3. In a door operating mechanism, the 25 combination with adjacent door members, one of which is movable relatively to the other; of operating mechanism comprising an actuating element mounted upon one of said members and confined to limited longitudinal movement in opposite directions 30 with respect thereto, said element being arranged when moved in one direction to abut said other member for forcing the members apart; and a second element movably 35 mounted on the other of said members and adapted to be detachably connected with said first element and moved with said first element when the same is moved in the opposite direction for forcing said members 40 toward each other; and means for imparting longitudinal movement to said first element in opposite directions.
4. In a door operating mechanism, the 45 combination with adjacent door members, one of which is movable relatively to the other; of operating mechanism comprising an actuating element mounted upon one of said members and confined to limited longitudinal movement with respect thereto in 50 opposite directions, said element being arranged in the plane of said other member and adapted to directly abut the same for forcing the members apart, said element being provided with a projection extending 55 to one side of the plane of said other mem-
- ber; a second element mounted on the other of said members to swing in a plane substantially parallel to said first element, and having a portion adapted to be detachably connected with the projection upon said first 60 element whereby movement of said first element will move said members together; and means mounted on said first member for moving said first element in opposite directions. 65
5. In a door operating mechanism, the combination with adjacent door members, one of which is movable relatively to the other; of operating mechanism comprising an actuating element mounted upon one of 70 said members and adapted for movement in opposite directions, said member when moved in one direction bearing against said other member for forcing said members apart; and a second element mounted on the 75 other of said members and provided with a plurality of spaced means arranged for detachable and adjustable connection with said first element; and means for imparting movement to said first element in opposite 80 directions.
6. In a door operating mechanism, the combination with adjacent door members, one of which is movable relatively to the other; a housing fixed to one of said members; a reciprocable rack bar mounted within said housing in the plane of said other member, said bar when moved in one direction being adapted to abut the front edge 85 of said other member for forcing the members apart, said rack bar being provided with a projection extending to the outer side of the plane of said other member; a lever pivotally mounted with respect to said housing and having means for imparting reciprocation to said rack bar in opposite directions; and a latch member pivotally mounted within the forward edge of said other member and arranged to swing in a plane 90 substantially parallel to the plane of movement of said first element, said second element being provided with hooked means adapted for detachable connection with the projection on said first element for moving said members together upon movement of 95 said rack bar in the opposite direction. 100

In witness that I claim the foregoing I have hereunto subscribed my name this 30 day of July, 1923.

BARTHOLOMEW JULIEN.
